To all whom it may concern:

Be it known that I, Helen A. Dodge, a citizen of the United States, residing at Piedmont, State of California, have invented a new, original, and ornamental Design for a Bedroom Slipper, of which the following is a specification, reference being had to the accompanying drawing, forming a part hereof.

Fig. 1 is a plan view of a bedroom slipper showing my new design.

Fig. 2 is a side elevational view of same.

Fig. 3 is an end elevational view of same.

The dominant feature of the design resides in the portion shown in full lines.

I claim:

The ornamental design for a bedroom slipper, as shown and described.
